CLAIM

The ornamental design for a glue gun, as shown and described.

DESCRIPTION

FIG. 1 is a perspective view of a glue gun showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

The broken lines represent portions of the glue gun that form no part of the claimed design.
